UNITED STATES PATENT OFFICE.

NICOLAS FRANCOIS, OF BRESSOUX, NEAR LIEGE, BELGIUM.

ROTARY-VALVE DISTRIBUTING DEVICE FOR COMPRESSED-AIR AND LIKE ENGINES.

Application filed February 1, 1924. Serial No. 689,973.

To all whom it may concern:

Be it known that I, NICOLAS FRANCOIS, a subject of the King of the Belgians, residing at Bressoux, near Liege, Belgium, have invented new and useful Improvements in 5 Rotary-Valve Distributing Devices for Compressed-Air and like Engines, of which the following is a specification.

The present invention relates to an improved rotary valve distributing device for compressed air and like engines with single or multiple cylinders, and more particularly to a rotary valve distributing device of the cylindrical type, provided with circumferential ports and recesses or channels controlling the admission, the expansion and the exhaust of the air or other driving fluid, a single device of this kind being sufficient for any number of cylinders.

20 The essential feature of the rotary valve distributing device according to the invention resides in the particular construction and arrangement of its parts, whereby the rotation in one direction, the stopping, and 25 the rotation in the other direction of a compressed air engine may be obtained by imparting an angular movement to one of the concentric cylinders constituting the device, the particular arrangement of the ports making 30 possible to obtain on starting the engine a longer period of admission than during normal running, with a view to avoiding dead centers.

In order that the invention may be readily 35 understood, one embodiment of same is, by way of example only illustrated by the accompanying drawings, wherein:

Fig. 1 is a longitudinal section of a rotary valve distributing device according to the 40 invention, which is in the present case placed above the cylinders and co-axial therewith.

Fig. 2, Fig. 3, Fig. 4, Fig. 5 and Fig. 6 are transverse sections through the same device showing the parts in the positions which 45 they occupy respectively when the engine is stopped, during the admission period on the engine being started, during the admission period when the engine runs normally, during the expansion period and during the 50 exhaust period.

Referring to the said drawings, the device comprises three concentric cylinders, of which the first *a* is driven by the engine and rotates in the present instance at the same speed as that of the latter, while the second

b is stationary and the third *c* is capable of having a predetermined angular movement or fractional rotation imparted thereto by means of a suitable operating lever *d* integral therewith or suitably fixed thereon. 60

The three cylinders *a*, *b*, *c* are mounted in a casing *e* which may or may not be cast integral with the cylinders 1, 2, 3, 4 of the engine, and is provided with ports *f* communicating with the said cylinders and 65 with ports *g* communicating with the exhaust pipe *h*.

The inner cylinder *a* is hollow and closed at both ends; a set of ports *i*, which are also provided in the cylinders *b* and *c* permits 70 the admission of compressed air or other driving fluid via the inlet *k* provided in the casing *e* and by way of the circular groove *l* cut in the said casing.

The said cylinder *a* is also provided with 75 ports *m* for the admission of the air at the required moment in each cylinder of the engine via the ports *n*, *n'* or *o*, *o'* of the intermediate cylinder *b*, according to which one or ones of these ports register with the 80 corresponding port *p* or *p'* of the outer cylinder *c*, and by way of the circular grooves *q* and ports *f* of the casing *e*.

The inner cylinder *a* also has longitudinal recesses or grooves *r* communicating with circular grooves or channels *s* which in turn communicate with the exhaust pipe *h* via ports *t* in the cylinders *b* and *c*, circular grooves *u* cut in the casing *e*, and the 85 ports *g*.

These recesses *r* serve to obtain the exhaust at the required moment through the same ports *n*, *n'* or *o*, *o'* and in a manner similar to the admission. The ports *n*, *n'* and *o*, *o'* form two sets of ports corresponding to the two different directions of rotation of the engine; the ports *n* and *o* are made to serve when the engine runs normally and the ports *n'* and *o'* respectively serve for obtaining a longer period of admission, i. e. for forcing the admission, on starting the engine. 90

Thus, if the outer cylinder *c*, which is as stated capable of angular adjustment by means of the lever *d*, is moved in the direction of the arrow *x* when the inner cylinder *a* is rotating in the direction of the arrow *z* (see Fig. 3), at a given moment the port *n'* and a portion of the port *n* will be uncovered by the port *p* and while the passage 100

105

110

for the admission is reduced the latter will have a duration proportional to the angle β .

If the said movement of the outer cylinder c is continued until the port p exactly registers with the port n , the additional port n' at the same time becoming obturated (see Fig. 4), the period of admission will be proportional to the angle α smaller than the angle β by the quantity γ and corresponding to the normal running of the engine. It is obvious that the size of the additional port n' or o' determines the angle of admission proportional to the increased period of admission on starting the engine.

When in practice and for mechanical reasons the distributing device will have to rotate at half or a third of the speed of the engine, the said device would be provided with two or three series of the above described distribution ports.

I claim:

1. In a rotary valve distributing device for compressed air and like engines, the combination of: a casing having communications with the engine cylinders and the exhaust pipe; an inner rotary distributing cylinder driven by the engine and having admission ports and exhaust channels formed therein; a stationary intermediate cylinder arranged concentrically to said inner cylinder and having ports corresponding to each direction of rotation of the engine formed therein; and an outer cylinder having communication ports formed therein, mounted within the aforesaid casing concentrically to the two first-named cylinders and capable of angular adjustment in relation thereto whereby said communication ports may be brought to register with such of the ports of the intermediate cylinder as will correspond to the rotation of the engine in whatever direction is desired; substantially as described.

2. In a rotary valve distributing device for compressed air and like engines, the combination of: a casing having communications with the engine cylinders and the exhaust pipe; an inner rotary distributing cyl-

inder driven by the engine and having admission ports and exhaust channels formed therein; a stationary intermediate cylinder arranged concentrically to said inner cylinder and having pairs of sets of ports of which each set of a pair corresponds to one direction of rotation of the engine; and an outer cylinder having communication ports formed therein, mounted within the aforesaid casing concentrically to the two first-named cylinders and capable of angular adjustment in relation thereto whereby said communication ports may be brought to register with such sets of the "pairs of sets" of ports in the intermediate cylinder as will correspond to the rotation of the engine in whatever direction is desired; substantially as described.

3. In a rotary valve distributing device for compressed air and like engines, the combination of: a casing having communications with the engine cylinders and the exhaust pipe; an inner rotary distributing cylinder driven by the engine and having admission ports and exhaust channels formed therein; a stationary intermediate cylinder arranged concentrically to said inner cylinder and having pairs of sets of ports of which each set of a pair corresponds to one direction of rotation of the engine and comprises a port for normal running and an additional port for obtaining a forced admission on starting the engine; and an outer cylinder having communication ports formed therein, mounted within the aforesaid casing concentrically to the two first-named cylinders and capable of angular adjustment in relation thereto whereby said communication ports may be brought to register with either the port for normal running alone or the additional port as well of the sets of ports of the intermediate cylinder corresponding to the desired direction of rotation of the engine; substantially as described.

In testimony whereof I signed hereunto my name.

NICOLAS FRANCOIS.
